UNITED STATES PATENT OFFICE

CHARLES F. SMITH, OF BROOKLYN, NEW YORK, ASSIGNOR TO LILY-TULIP CUP CORPORATION, OF NEW YORK, N. Y., A CORPORATION OF DELAWARE

PAPER CUP MACHINE

Application filed February 12, 1930. Serial No. 427,687.

The object of this invention is to furnish improved mechanism for turning in and closely folding down the rims of paper cups, and is in the nature of an improvement upon portions of the operating mechanism of the paper cup machine disclosed in my copending application Serial No. 181,475 filed April 6, 1927. The machine of such prior application is designed to concurrently perform work upon the cup forming material at each of a number of stations through which the material for each cup progressively passes until the cup is discharged as a finished product. The present improvements relate to mechanism for accomplishing one major result in the finished cup—a closely folded in-turned rim—in two major operations at two stations.

In the drawings accompanying this specification a form of machine which has been used for carrying out my invention and which may be regarded as the preferred form is illustrated, in which drawings,

Figure 1 is a top view of part of a cup making machine showing a segment of a rotary carrier upon which are mounted two cup holders respectively located at two work stations, which stations are equipped with a form of mechanism for carrying out my present invention.

Fig. 2 represents the nearly finished cup which is to be finished at the two stations illustrated.

Fig. 3 is a representation of the cup after being worked upon at the first station.

Fig. 4 shows the cup after having been finished at the second station.

Fig. 5 is an elevation showing the mechanism of the first station.

Fig. 6 is a horizontal section taken on a plane at about the line 6—6 of Fig. 5.

Fig. 7 is a similar section taken at about the plane of the line 7—7.

Fig. 8 is an elevation of the mechanism of the second station.

Fig. 9 is a vertical section on an enlarged scale of the first station.

Fig. 10 is a face view of the left-hand end of the head represented in Fig. 9.

Fig. 10a is a further enlarged sectional detail of this head.

Fig. 11 is an enlarged vertical section of the second station.

Fig. 12 is a detail showing some of the parts represented in Fig. 11. In Fig. 11 the mandrel and pressing guide are about to enter the cup. In Fig. 12 these parts have entered the cup and are shown as having practically completed their work, and

Fig. 13 is a face view of the left-hand end of the head represented in Fig. 11.

The particular form of cup illustrated in Figs. 2, 3 and 4 has a body portion 15 formed from a number of sheets of paper one about the other, the top edge or brim of the cup being formed by turning inwardly a portion 16 located at the outer edge and closely folding this down upon the body, see Fig. 4.

While my present improvements are adapted to be used upon various types of round paper bodies, and may be used in connection with various kinds of forming and holding devices, yet they are peculiarly adapted for use in the machine described in my copending application above identified.

In the drawings the device for holding the cups is designated by the reference character 17. A plurality of these cup holders are generally employed in cup making machines, and are mounted upon a circular rotary carrier, a segment of the carrier being shown in Figure 1 and designated 18, upon which carrier two cup holders 17 are represented and are assumed to be mounted radially of the axis of the rotation of the carrier 18.

In Fig. 9 the first portion of the operation is illustrated, namely, that of turning inwardly the outer edge 16 of the cup seen in Fig. 2, this being accomplished at the first station. The product, Fig. 3, of the first station is shown at the second station in Fig. 11, and the completed product, Fig. 4, of the second station, in which the inturned flange has been closely folded down at the rim of the cup, is represented in its final formative stage in Fig. 12.

It will be assumed that the cup holders 17 are continuously rotated in some convenient manner, preferably by power applied

to their shafts 19. The mechanism for turning in the rim of the paper cup comprises, see Figs. 9 and 10, a compound die comprising a shell 20 carrying a number of inwardly directed fingers 21, and as these fingers resemble, in a way, cogs of an internal gear, they may, for want of a better name, be called internal cogs. A plunger 22 is mounted within the shell 20, and is furnished with fingers or external cogs 23, extending into the spaces between the fingers or internal cogs 21. The spaces between some of the cogs 21 are cut more deeply than the other spaces. In the illustration one set of alternate spaces is deeper than the other. The cogs 23 are similarly illustrated, each alternate cog being longer than those on each side of it, the longer cogs occupying the deeper spaces. Formed in the forward radial or working face of the set of cogs 21 is a rounded cavity 23' for engaging the edge 24 of the cup rim and for supporting and directing its inward turning, which turning is then completed by means of the advance of the plunger 22 and the cogs 23. The outer ends of the longer cogs 23 are shown as forwardly curved at 23'', (see Fig. 10a).

It is assumed that the carrier 18 advances intermittently, indexing the cup holders 17 into the various stations and holding them during the operation of the work performing mechanisms located at the stations. In the turning in mechanism of the first station herein illustrated, the shell 20 is furnished with a rearwardly extending shank 25 which is mounted for reciprocation and free rotation within a bearing 26 which is upstanding from a base member 27 mounted for adjustment on the machine frame 28. The stem or shaft 29 of the plunger 22 extends through the hollow bore of the shank 25 where it finds a bearing and also in a bearing member 30 upstanding from the base 27. The shaft 29 is adapted to reciprocate within these bearings and also to rotate either with the shell 20 and shank 25 or independently of these. For the purpose of preventing overthrow of the shaft 29 its rear end passes through a cap 300 carried by the bearing member 30, the cap supporting a key 301 passing through a longitudinal keyway 302 formed in the shaft.

Upon a cup holder presenting an unfinished cup, as for instance that shown in Fig. 2, to the first station, the compound die within the shell 20 is advanced for engagement with the edge 24 of the cup, whereupon the turning in operation commences. The advance of the shell is effected by shifting the stem or shank 25 toward the left to the position shown in Fig. 9, the shell with its internal cogs 21 being held in advance of the plunger with its cogs 23 by means of a coiled spring 31 between the face 32 of a shifting member and the rear end face 33 of the shank 25. The spring is

of sufficient strength to cause the compound die to effect the turning in movement prior to the engagement of the cup by the plunger 22. After the brim 16 has been turned in a sufficient amount, the resistance encountered by the shell 20 by its engagement either with the work or with the front end of the cup holder 17 halts the advance of such shell, while the plunger 22 advances and moves the working faces of the cogs 23 beyond the working faces of the cogs 21, thus completing the initial inward bending or turning of the brim 16.

The reciprocating movement of the stem or shaft 29 is effected in the following manner, particular reference being had to Figure 1, first station, and to Figs. 5, 6, 7 and 9:

A ring 33' having a groove in it for the engagement of a shifter is mounted on the shaft 29 and held in position by a pair of locknuts 34. The shifter fork 35 carries a pair of engaging members 36 running in the groove of the ring 33'. The shifter fork is mounted on a rock shaft 37 extending downwardly through the machine frame and at its lower end carrying a rock arm 38. The rocking of the arm 38 is effected in the following manner, the power coming from what may be termed the main shaft 39 which is driven in some convenient manner and carries a miter gear 40 meshing with a miter gear 41 fast on a shaft 42. The shaft 42 has at its other end a miter gear 43 meshing with a miter gear 44 mounted on the end of a tubular shaft 45 which surrounds the shaft 37 and is interposed between a portion of the lower end of the shaft 37 and its lower bearing 45'. A rock shaft 46 is mounted substantially parallel to the shafts 37, 45, and carries a rock arm 47 having a cam engaging member 48 running in a cam groove 49 in a cam wheel 50' fast upon the shaft 45. The lower end of the rock shaft 46 carries a rock arm 50 which is connected by means of a link 51 to the rock arm 38 whereby continuous rotation of the shaft 45 through the instrumentality of the cam groove 49 and rock arm 47 imparts an oscillatory movement to the shaft 46 and rock arm 50, which in turn and through the link 51 rocks the arm 38, the shaft 37 and shifter fork 35.

The cam groove 49 is shown having two circular portions 52, 53, the portion 52 being located nearer the center of the axis of the shaft 45 than is the portion 53, and the portion 53 is shown as of less extent. The proportions are such that the turning in mechanism is advanced quickly to the work, held at the working position for a short time by means of the circular portion 53, and quickly withdrawn from the work and held in the idle position for a longer time by means of the more extended portion 52.

The folding down mechanism which may be termed an ironing down of the partially

turned in rim is illustrated at the second station in Figure 1 and in Figs. 8, 11, 12 and 13. After the withdrawal of the compound die comprising the shell 20 and plunger 22 from the cup acted upon at the first station, the carrier 18 advances one step and moves the cup into the second station, see Fig. 11, whereupon a combined folding and pressing device, which is positively rotated, acts upon the inturned rim. The folding and pressing mechanism comprises a wheel 60, having a bevelled edge 61 adapted to preliminarily engage the inturned rim 16, and a perimeter 62 adapted to follow along the entire extent of the rim and fold this against the body of the cup. In cooperation with the wheel are a number of jaws or pressing members 63 which move outwardly and engage the outer portion only of the rim for bending this more sharply. The operative head at the second station is shown supported by a casting 64 having at its rear a bearing 65 which supports one end of a sleeve or tubular shaft 66, the other end of such shaft being supported in a bearing block 67 having a portion passing through an opening in an upstanding end 94 of the casting 64 and a flange bolted against the face of such end. The sleeve shaft 66 has a collar 68 formed upon it for engaging the bearing block 67 which prevents movement in one direction. Movement in the other direction is prevented by the body portion 69 of a miter gear 70, the miter gear being fast upon the sleeve shaft 66 and its body portion 69 engaging the face of the bearing 65.

Rotation is imparted to the miter gear 70 and sleeve shaft 66 by means of a miter gear 71 fast upon the upper end of a shaft 72 which carries at its lower end a bevel pinion 73 in mesh with a bevel wheel 74 fast on the shaft 75 which is driven from the main shaft 39 by means of a bevel gear 76 meshing with a bevel pinion 77 fast on the shaft 75.

There is shown mounted within the sleeve shaft 66 and projecting from both its ends a shaft 78. The shaft 78 is adapted to rotate with the sleeve shaft 66 in which it has its bearing, but is capable of longitudinal reciprocation therein, it having a longitudinal slot 79 which receives a key or pin 80 carried by the sleeve 66.

The longitudinal movement of the shaft 78 is effected by means of a shifting ring 81 fast upon its outer end. The shifting lever 82 which has a fork 83 for engaging the groove 84 in the ring 81 is pivoted to the machine frame at 85 and is operated from a cam wheel 86 rotated by means of a bevel gear 87 driven by a bevel pinion 88 mounted on the shaft 75. A suitable roller or cam pin 89 engages the cam groove 90 in the wheel 86, the roller 89 being carried by a link 91 pivoted to the lower end of the lever 82.

The folding wheel 60 described above is

mounted upon the inner end of the shaft 78.

The pressing device 63 which moves somewhat in the nature of chuck jaws is mounted and operated in the following manner:

A support is shown, see Fig. 11, in the nature of an internally screw threaded sleeve 92, formed with an enlarged base 93 surrounding the flange at the bearing block 67 and secured to the face of the upstanding portion 94 of the casting 64. Within the sleeve 92 there is mounted a tubular member 95 having screw threaded engagement with the sleeve 92 and having an inturned flange 96 at its outer end which forms a bearing and support for a housing shell 97. The inner portion of this housing shell is of reduced outer diameter and carries a thrust bearing shown comprising a pair of rings 98, 99 between which there is a set of balls 100. One of these rings engages a shoulder at the reduced rear end of the shell; the other end is engaged by a screw nut 101. On the forward movement of the housing shell 97 the thrust bearing ring 98 engages the inturned flange 96, thus affording an antifriction stop, see Fig. 12. The shell 97 is caused to rotate with the shaft 78 by means of a key 78' which engages a suitable keyway in such shell, and which it may freely traverse to permit independent axial movement of the shaft.

Each of the pressing members 63 is formed on its inner end with a bevel face 102 engaging the beveled enlarged end 104 of the shaft or stem 78 located immediately behind the folding wheel 60. Each of these pressing devices 63 is securely fastened to a body block 105, such body block being located in suitably formed slots in the shell 97 and each mounted upon a pivot pin 106. These body blocks 105 are so formed that their individual movement and the inward movement of the pressing devices is in a measure controlled by their engagement with the stem 78. Their outward movement is controlled by a ring 107 which is screwed into the end of the member 97. The ring 107 is engaged by pins 108 upon which are mounted coiled springs 109 seated within the blocks 105 and adapted to move the blocks inwardly upon the retraction of the tapered head 104. The ring 107 also serves to limit the outward movement of the blocks 105 to which the jaws 63 are secured. The outer ends of these blocks extend outwardly radially so as to form an enlarged or long supporting surface for the jaws 63.

The forward end of the shaft or stem 78 is formed of reduced diameter, as at 110, leaving a forwardly facing shoulder which is shown engaging the rear face of a block 111 for enabling the shaft or stem to press the block forward. The block is shown formed with a number of pockets 112 in which are mounted compression springs 113, such springs being adapted to elastically or yieldingly advance a plate 114 upon the advance 120

of the shaft or stem 78. These springs are steadied by means of pins 115 carried by the plate 114 and protruding through rearwardly formed openings in the back of the block 111.

5 The operation of the mechanism shown in Figures 11, 12 and 13 is substantially as follows:

When the cup is brought to the Fig. 11 station with the rim 16 as it was turned in at the 10 first station, and while the various parts at the second station continue to rotate, the cam wheel 86 advances the shaft or stem 78 thereby causing the wheel 60 to enter the inturned rim. The bevelled face 61 of the wheel 60 15 first engages the rim; afterwards the full perimeter 62 of the wheel engages such rim. During this forward movement of the shaft, the shoulder on such shaft engages the block 111 and the tapered head 104 engages the jaws 20 but without lifting the same, the springs 113 being strong enough to resist compression during such forward movement and prevent relative movement between the shaft and the shell 97. When the forward faces of the jaws 25 63 engage the holder 17, further forward movement of the shell 97, upon which these jaws are pivoted through the blocks 105, is prevented, whereupon the shaft 78 advances relatively to such shell, the springs 113 being compressed, and the tapered head 104 expands 30 the jaws against the inturned rim of the cup along the creased edge thereof. The rim is thus pressed or ironed down and made as compact as the nature of the material of which it 35 is formed will permit.

Although but one form of my invention is shown in the drawings, which is designed for use in an existing machine, yet the improvements are capable of wider use as may be required and variations may be made as occasion requires within the scope of the claims without departing from the spirit of the invention.

Having described my invention, I claim 45 and desire to secure by Letters Patent:

1. In a paper cup machine, the combination with a series of cup holders, and a carrier adapted to bring these sequentially into the working stations of the machine, of means at 50 one station for preliminarily turning inwardly the rims of unfinished paper cups presented by such holders and comprising a compound die embodying an outer member and a plunger mounted for independent longitudinal movement therein, a plurality of inwardly directed fingers carried by the outer member and having a recess in their forward face for engaging the edge of a cup and starting an inward bend, a plurality of outwardly 55 directed fingers carried by the plunger and interfitting with the inwardly directed fingers and adapted on the independent forward movement of the plunger to complete the inward bending, and means at a succeeding station for folding down the rims inturned at a

previous station, and comprising a shaft, and means for rotating and for reciprocating the shaft, a wheel on the shaft constructed and adapted to enter the cup and in so doing engage the inturned rim and fold it down, a body surrounding the shaft, and means connecting the body to the shaft for rotation therewith, the connecting means permitting free independent axial movement of the shaft, elastically yieldable means actuated by the shaft and active on the body for causing it to move forward with the shaft and wheel, the parts being so formed that such movement is halted by the cup holder, a series of outwardly movable jaws mounted on the forward end of the body and rearwardly of the wheel, and means associated with the shaft for opening the jaws and pressing them against the outer edge of the inturned rim upon the forward axial movement of the shaft independently of the body carrying such jaws. 70 75 80 85

2. In a paper cup machine embodying a number of working stations, means at one station comprising a compound die for preliminarily turning inwardly the rims of paper cups by a two-step operation, and cooperatively associated means at a second station for folding down by a two-step operation the rims inturned at the previous station. 90

3. In a paper cup machine embodying a number of working stations, means at one station for preliminarily turning inwardly the rims of paper cups by a two-step operation, and consisting of a compound die comprising a shell and a plunger, the shell being furnished with fingers resembling internal cogs having a recess in their forward face for engaging the edge of a cup and starting an inward bend, and the plunger being furnished with fingers resembling external cogs 100 interfitting with the cogs carried by the outer member and adapted on the independent forward movement of the plunger to complete the inward bending of the edge of the cup, and cooperatively associated means at a second station for folding down by a two-step operation the rims inturned at the previous station. 105 110

4. In a paper cup machine embodying a number of working stations, means at one station for preliminarily turning inwardly the rims of paper cups by a two-step operation, consisting of a compound die comprising a shell and a plunger, the shell being furnished with fingers resembling internal cogs having a recess in their forward face for engaging the edge of a cup and starting an inward bend, and the plunger being furnished with fingers resembling external cogs 115 120 125 130

interfitting with the cogs carried by the outer member and adapted on the independent forward movement of the plunger to complete the inward bending of the edge of the cup, 5 and cooperatively associated means at a second station for folding down by a two-step operation the rims inturned at the previous station.

5. In a paper cup machine embodying a 10 number of working stations, means at one station comprising a compound die for preliminarily turning inwardly the rims of paper cups by a two-step operation, and cooperatively associated means at a second station for 15 folding down by a two-step operation the rims inturned at the previous station, comprising a continuously rotating axially movable wheel adapted to enter a paper cup and roll upon and fold down the turned in rim 20 of the cup, and a set of jaws adapted to follow the wheel into the cup and iron the folded down rim at and adjacent its outer margin.

6. In a paper cup machine, the combination 25 with a series of cup holders and a carrier adapted to bring these sequentially into the working stations of the machine, of means at one station for preliminarily turning inwardly the rims of paper cups, and means at 30 a succeeding station for folding down the rims inturned at a previous station, said second-mentioned means comprising a shaft, means for rotating and for reciprocating the shaft, a wheel on the shaft constructed 35 and adapted to enter the cup and in so doing engage the inturned rim and fold it down, a body surrounding the shaft, means connecting the body to the shaft for rotation therewith, the connecting means permitting free 40 independent axial movement of the shaft, elastically yieldable means actuated by the shaft and active on the body for causing it to move forward with the shaft and wheel, the parts being so formed that such movement is halted by engagement between the 45 body and the cup holder, a series of outwardly movable jaws mounted on the forward end of the body and rearwardly of the wheel, and means associated with the shaft for opening 50 the jaws and pressing them against the outer edge of the inturned rim upon the forward axial movement of the shaft independently of the body carrying such jaws.

7. In a paper cup machine, the combination 55 with a series of cup holders and a carrier adapted to bring these sequentially into the working stations of the machine, of means at one station for preliminarily turning inwardly the rims of paper cups, and comprising 60 a compound die embodying an outer member and a plunger mounted for independent longitudinal movement therein, a plurality of inwardly directed fingers carried by the outer member and having a recess in their 65 forward face for engaging the edge of a cup

and starting an inward bend, a plurality of outwardly directed fingers carried by the plunger and interfitting with the inwardly directed fingers and adapted on the independent forward movement of the plunger to complete the inward bending, and means at a 70 succeeding station for folding down the rims inturned at a previous station.

8. In mechanism for turning in and closely folding down the rims of paper cups, the 75 combination with a series of cup holders and a carrier for the cup holders adapted to index the cup holders sequentially into the working stations of the machine, of means at one station for preliminarily turning inwardly the rims of paper cups as these are indexed into such station, said means comprising a compound die embodying a shell and a plunger, the shell being furnished with fingers resembling internal cogs having a recess in their forward face for engaging the edge of a cup and starting an inward bend, and the plunger being furnished with fingers 80 resembling external cogs interfitting with the cogs carried by the outer member and adapted on the independent forward movement of the plunger to complete the inward bending of the edge of the cup.

9. In a paper cup machine the combination 85 with a cup holder, of a compound die 95 embodying two members, each formed with a circular series of fingers for engaging the edge of a paper cup, the fingers of the two series interfitting, means for positively advancing one of such members toward the cup 100 holder, elastically yieldable means associated with the advancing means and the other member for advancing it against the cup holder, the organization being such that the series of fingers carried by the elastically advanced member initially act upon the edge 105 of the cup, and that upon compression of the elastically yieldable means the fingers carried by the positively advanced member engage the edge and complete the turning in 110 operation for this station.

10. In a paper cup machine, a compound die 115 embodying two members, each formed with a circular series of fingers for engaging the edge of a paper cup, the fingers of the two series interfitting, means for positively advancing one of such members toward a positioned cup, elastically yieldable means associated with said members whereby the other member is held in advanced position 120 relatively to said positively advanced member, the organization being such that the series of fingers carried by the elastically advanced member initially act upon the edge of the cup, and that upon resistance being offered to the advance of said other member, said positively advanced member advances with compression of the elastically yieldable means, whereby the fingers carried by such 125 positively advanced member advance rela- 130

tively to the other member and engage the edge of the cup and complete the turning in operation for this station.

11. In a paper cup machine, the combination with a continuously rotating axially movable wheel adapted to enter a paper cup and roll upon and fold down the turned in rim of the cup, of a set of jaws adapted to follow the wheel into the cup and iron the folded down rim at and adjacent its outer margin.

12. In a paper cup machine, the combination with a continuously rotating axially movable wheel adapted to enter a paper cup and roll upon and fold down the turned in rim of the cup, of a set of jaws adapted to follow the wheel into the cup and iron the folded down rim at and adjacent its outer margin, a body rotatable with the wheel and upon which the jaws are pivotally mounted, elastically yieldable means for advancing the body upon the axial movement of the wheel, the jaws being formed with circumferential faces for entering the cup and ironing the folded down rim and also with radially disposed faces for engaging the outer margin and the crease of the rim, means located in position for halting the advance of the body, and means for thereafter expanding the jaws.

13. In a paper cup machine, the combination with a series of cup holders and a carrier adapted to bring these sequentially into the working stations of the machine, of means at one station comprising a compound die for preliminarily turning inwardly the rims of paper cups by a two-step operation, and means at the succeeding station for closely folding down the rims inturned at the previous station, said second mentioned means comprising a member constructed and adapted to enter the cup and in so doing engage the inturned rim and fold it down, a body, connecting means between the body and member for permitting free independent axial movement of the said member, elastically yieldable means for advancing the body upon the axial movement of the said member the parts being so formed and related that such movement of the body is halted by engagement with the cup holder, a series of outwardly movable jaws mounted on the forward end of the body, and means associated with said member for opening the jaws and pressing them against the outer edge of the inturned rim upon the forward axial movement of the member independently of the body carrying such jaws.

14. In a paper cup machine, the combination with a series of cup holders and a carrier adapted to bring these sequentially into the working stations of the machine, of means at one station comprising a compound die for preliminarily turning inwardly the rims of paper cups by a two-step operation, and

means at the succeeding station for closely folding down the rims inturned at the previous station, said second mentioned means comprising a wheel and means for rotating and reciprocating it, the wheel being constructed and adapted to enter the cup and in so doing engage the inturned rim and fold it down, a body, connecting means between the body and wheel for permitting free independent axial movement of said wheel, elastically yieldable means for advancing the body upon the axial movement of the said wheel, the parts being so formed and related that such movement of the body is halted by engagement with the cup holder, a series of outwardly movable jaws mounted on the forward end of the body, and means associated with said wheel for opening the jaws and pressing them against the outer edge of the inturned rim upon the forward axial movement of the wheel independently of the body carrying such jaws.

15. In a paper cup machine, the combination with a continuously rotating axially movable wheel and means for so moving the wheel as to cause it to enter a paper cup and roll upon and fold down the turned in rim of the cup, of a set of expandable jaws and means for forwarding these and causing them to follow the wheel into the cup and iron the folded down rim at and adjacent its outer margin, and means associated with the said wheel moving means for expanding the jaws after these have entered the cup.

16. In a paper cup machine, the combination with a series of cup holders and a carrier adapted to bring these sequentially into the working stations of the machine, of means at one station for preliminarily turning inwardly the rims of paper cups, and means at the succeeding station for closely folding down the rims inturned at the previous station, said second mentioned means comprising a wheel, means for rotating and reciprocating it, the wheel being constructed and adapted to enter the cup and in so doing engage the inturned rim and fold it down, a body, connecting means between the body and wheel for permitting free independent axial movement of such wheel, means for causing the body to move forward with the said wheel, the parts being so formed and related that such movement of the body is halted by engagement with the cup holder, a series of outwardly movable jaws mounted on the forward end of the body, and means associated with the wheel for opening the jaws and pressing them against the outer edge of the inturned rim upon the forward axial movement of the wheel independently of the body carrying such jaws.

17. In a paper cup machine, the combination with a series of cup holders and a carrier adapted to bring these sequentially into the working stations of the machine, of means

at one station for preliminary turning inwardly the rims of paper cups, and means at the succeeding station for closely folding down the rims inturned at the previous station, said second mentioned means comprising a continuously rotating axially movable wheel and means for so moving the wheel and causing it to enter a paper cup and roll upon and fold down the turned in rim of the cup,
5 a set of expandible jaws and means for forwarding these and causing them to follow the wheel into the cup and iron the folded down rim at and adjacent its outer margin, and means associated with the said wheel moving
10 means for expanding the jaws after they have entered the cup.
15

18. In a machine of the character described, the combination with a cup engaging die embodying a reciprocating plunger and shaft, of means for reciprocating these comprising a grooved shifter collar fast on the shaft, a rock shaft, a shifter fork on the rock shaft having fingers for engaging the groove in the collar, a sleeve shaft surrounding a
20 portion of the rock shaft, means for rotating the sleeve shaft, a wheel provided with a groove fast with the sleeve shaft, a rock arm carried by the rock shaft, a counter rock shaft, an arm carried thereby, a link connecting such arm and the rock arm, and a second arm carried by the counter rock shaft and having a cam engaging member running in
25 the cam groove.
